UNITED STATES PATENT OFFICE.

CARL F. RAKOW, OF WHEATLAND, NORTH DAKOTA.

GRAIN-CAR DOOR.

1,149,080.

Specification of Letters Patent. Patented Aug. 3, 1915.

Application filed February 12, 1914. Serial No. 818,203.

To all whom it may concern:

Be it known that I, CARL F. RAKOW, a citizen of the United States, residing at Wheatland, in the county of Cass and State 5 of North Dakota, have invented certain new and useful Improvements in Grain-Car Doors; and I do hereby declare the following to be a full, clear, and exact description of the invention, such as will enable others 10 skilled in the art to which it appertains to make and use the same.

My invention relates to new and useful improvements in doors for railway cars particularly grain cars.

15 An important object of my invention is to provide a door consisting of two sections that may be moved into open or closed position independently of each other.

Another important object of my invention 20 is to provide locking means for the door sections whereby the doors are firmly held in place, are prevented accidental derangement and may be expeditiously opened and closed.

25 Another important object of my invention is to provide novel means for supporting the doors when in open position, said doors being so supported as to take up little or no room thus enabling a great receiving 30 capacity for the car.

Another important object of my invention 35 is to provide a novel form of means for hanging the doors consisting of means whereby one of said doors may be swung and suspended interiorly of the car from the roof thereof and be slidably moved into an out of the way position and then suspended in parallel relation to and near the roof of the car interiorly thereof.

40 A still further object of my invention is to provide a car door of the character described which is simple as to construction, reliable and efficient in operation, strong and durable, and cheap to manufacture and in- 45 stall.

The above and additional objects are accomplished by such means as are illustrated in the accompanying drawings, described in the following specification and then more 50 particularly pointed out in the claim which is appended hereto and forms a part of this application.

With reference to the drawings, wherein I have illustrated the preferred embodiment 55 of my invention as it is reduced to practice, and throughout the several views of which

similar reference numerals designate corresponding parts: Figure 1 is a front elevation of my improved door showing it in assembled closed position, Fig. 2 is an inside 60 elevation of my improved door showing the same in locked position and a portion of the car in section, Fig. 3 is a transverse sectional view taken through the car showing the doors in unlocked and supported 65 position adjacent the roof of the car, Fig. 4 is a horizontal section taken through the car adjacent to the roof thereof showing the suspension or hanging means in fragmentary plan and the door in dotted lines 70 in open position, Fig. 5 is a sectional view taken on horizontal line 6—6 of Fig. 1 showing in detail a portion of the door locking means, Fig. 6 is a vertical fragmentary sectional view taken on vertical line 6—6 of 75 Fig. 1, Fig. 7 is a sectional view taken on line 7—7 of Fig. 2, Fig. 8 is a horizontal fragmentary sectional view showing the laterally 80 slideable sealing plates to seal the crack of the door sections, and Fig. 9 is a detail perspective view of the wrench employed for operating the locking mechanism for the doors.

Referring to the drawings by characters of reference, the numeral 1 designates as an 85 entirety the door frame of a car in which is mounted my improved door consisting of a lower rectangular door section 2 and an upper larger rectangular door section 3. The sections 2 and 3 are designed to co-operate to close a portion of the opening in 90 the door frame after the usual manner and are arranged to be opened and closed independently of each other as will be later more fully described.

As a means for locking the door sections 95 2 and 3 within closed position in the door frame 1, I provide locking mechanism for each section which is identical as to construction. The locking mechanism consists of vertical slideable bars 4 and 5. The bars 100 4 and 5 are slideably mounted upon the outside faces of the sections 2 and 3 and each bar has operating in conjunction therewith a pair of locking plates 6 and 7. Each of these locking plates is secured by suitable fastening means 8 intermediate its ends transversely of the bars 4 and 5 adjacent the ends thereof so as to provide locking 105 tongues projecting with relation to the outer longitudinal edges of the bars 4 and 5 and arranged to fit within a recess 10 formed in the door frame 1. The plates 6 and 7 are

offset as at 11 and extend inwardly from the bars 4 and 5 toward the center of the door and in engagement with the outer face of the door sections. The plates in being offset fit about the inner longitudinal edges of the bars 4 and 5 as clearly shown in Fig. 6 in the drawings. The inwardly extending portions of the plates 6 and 7 are designated 12 and slidable through angular guide plates 13 that are secured upon the outer face of the door sections 2 and 3 in pairs. The guide plates 13 are arranged longitudinally of the door sections with their inner longitudinal edges spaced from each other. The portions 12 of the plates 6 and 7 are corrugated upon their outer faces as at 13' and as particularly shown in Fig. 6 in the drawings. The corrugated portions are longitudinally slotted with relation to each of the plates 6 and 7.

Screw threaded bolts 14 are inserted through the space comprehended between the inner edges of the plates 13 and the slots in the corrugated portions 13' of the plates 6 and 7 and preferably the door sections 1 and 2. The outer end of the bolt is enlarged to provide a head 15 so as to prevent the removal of a locking lever 16 which is turned upon each bolt. An elongated corrugated plate 17 is mounted upon each bolt 14 between the locking lever 16 and corrugated faces 13' of the plates 6 and 7. It will be readily seen that when the locking lever 16 is turned to bring the corrugated plate 17 into cooperating engagement with the corrugated surface 13' of the plates 6 and 7, the locking plates will be held in locked position. Suitable brace rods or bars 18 are arranged upon the inner faces of the door sections to provide strength for the door structures. The sliding bars 4 and 5 as will be readily seen with reference to the foregoing description and accompanying drawings are held against accidental derangement by means of the guide plates 13 for the locking plates 6 and 7.

As a means for sliding the bars 4 and 5 in such a way that the locking tongues 9 move into the recesses 10 in the sides of the door frame 1, I provide in connection with each door section an operating shaft 19 that is journaled in a bearing member 20 which is arranged centrally of the ends of each door section. The operating shaft 19 is provided with screw threads 21 at each end, said screw threads being arranged in opposite directions. Carried centrally of the ends of each of the bars 4 and 5 is an approximately U-shaped operating rod receiving member 22 that is secured at its free end by suitable fastening means 23 and provided centrally of its ends with an approximately cylindrical enlarged and internally screw threaded portion 24. The portions 24 of the members 22 receive the screw threaded

ends 21 of the operating shaft 19. Fixed upon the shaft 19 upon opposite sides of the bearing member 20 are angular faced wrench fitting portions 25 and 26 or if desired the shaft 19 may be formed with angular faces arranged to coöperate with a wrench or some other suitable tool. Carried upon the shaft 19 is an operating wrench 27 that is secured against removal relative to the shaft by means of a U-shaped securing bracket 28 secured at its ends to the wrench 27 and surrounding the shaft 19. The wrench 27 is provided with a long handle portion and as will be clearly seen is adapted to coöperate with the wrench fitting portions 25 and 26 upon the shaft 19 to bring about the rotation of the shaft. It will be readily seen that when the wrench 27 is positioned as described and operated to rotate the shaft 19 that the locking tongues are moved into and out of engagement with the recesses 10 in the sides of the door frame 1 according to the way in which the shaft is rotated.

As a means for insuring the perfect sealing of the door with the frame and also bracing the door sections I have provided upon each side of the door frame a pair of plates 28 and 29. The length of the plates 28 and 29 is equal to the height of the sections 2 and 3. The plates 28 overlap at their lower edges the upper edges of the plates 29. The plates 29 are provided adjacent their ends with transverse slots 30 through which screw threaded bolts or pins 31 are inserted for the purpose of securing the plates to the door frame. Nuts 32 having handle portions 33 thereon are turned upon the screw threaded bolts or pins 31 and serve to clamp the plates 28 and 29 in operative or out of the way position. The plates 28 and 29 in being arranged upon the inner edges of the door frame serve to seal the door with respect to the frame and brace the door in a reliable manner.

It will be readily seen with reference to the foregoing description and accompanying drawings that the door sections may be locked in a reliable and expeditious manner and in such a way that accidental derangement thereof is positively prevented. The unlocking of the doors is also provided in an expeditious manner. A pair of hinged bars 34 and 35 is secured in any suitable manner at the ends of the bars to the lower door section 2 adjacent the end thereof. The bars 34 and 35 are hinged as at 36 intermediate their ends and are secured at their upper ends to the crank portions of a crank rod 37. The crank rod 37 is carried by suitable brackets upon the horizontal piece of the door frame 1 at the upper part of the frame and is provided with suitable crank portions to which are secured the upper ends of the bars 34 and 35. The bars 34 and 35

- extend laterally from their secured ends or in other words are offset from their secured ends to provide for the proper fitting of the upper door section 3 and so as to prevent interfering of the bars 34 and 35 with the locking mechanism for the upper section. The crank rod 37 provides for the proper positioning of the lower door section 2 so that the locking thereof may be readily had.
- 5 The arrangement also permits the door section 2 to be swung inwardly with relation to the car and disposed adjacent the roof of the car after a manner which will be later described.
- 10 The upper door section 3 is arranged to slide longitudinally of the car to and away from the door frame 1. Secured at their lower ends to the inner face of the upper section 3 are supporting bars 38 and 39 which are arranged vertically with relation to the car and hinged as at 40 intermediate their ends but adjacent to the upper ends thereof. A second hinge as at 41 is provided for the bars 38 and 39 at a point between the hinges 40 and upper ends of the bars. This second hinge arrangement is for a purpose to be later described. The upper ends of the bars 38 and 39 extend through longitudinal slots formed in the under face 30 of a longitudinal track member, into said track member and have journaled thereon rollers 42. The track member is designated 43, is rectangular in cross section and is secured to the roof of the car along the upper 35 edge of the door frame. A lateral flange 44 is carried by the member 43 and has fastening means inserted therethrough for the purpose of securing the member 43 after the manner described.
- 40 The member 43 is of sufficient length to permit the door to be moved free of the door frame upon one side thereof. It will be readily seen that the upper door section 3 through the medium of the hinges 40 and 45 41 in the bars 38 and 39 may be swung outwardly with relation to the interior of the car into a position whereby it may be locked in the door frame or swung inwardly so that it may be slidably moved into and out of the 50 way position relative to the door frame. The hinges 40 and 41 provide for the hanging of the upper section 3 relative to the roof of the car as will be later more fully described.
- 55 Secured interiorly of the car adjacent to the roof thereof are transversely arranged rods arranged in pairs on opposite sides of the door frame, the rods of one pair being designated 45 and the rods of the other pair 60 being 46. Slidable upon and secured to the rods 45 and 46 are supporting rods 47 and 48 that are secured at right angles to and upon the rods 45 and 46 respectively and arranged so as to be moved upon the rods 45 and 46 in such a manner that the door sec-
- tions may be swung into the car and adjacent to the roof thereof. In the rods 45 and 46 at suitable points thereon are formed U-shaped loops 49 designed to receive the rods 47 and 48 to hold them in place when the desired adjustment is had.
- Rods 50, two in number preferably are slidable upon and secured to the rods 45 and 46 that are opposed to one another. With particular reference to Fig. 4, wherein I have shown a fragmentary plan view of the rod supporting arrangement, one of the rods 45 is left off and only a part of the rods 45 and 46 are shown. Two pairs of the rods 50 are employed and these rods and the missing rod 45 are the only elements not shown in this view. The door sections 2 and 3 are supported upon the rods 50 and 48 respectively after the door has been pushed inwardly and the larger section 3 moved over to one side of the door frame. The means described enables the supporting of the doors on both sides of the car as will be clearly seen. The upper door section 3 is caused to slide out of the way with relation to the door frame and is then swung upwardly and positioned after the manner described.
- The arrangement for supporting the doors described eliminates the taking up of too much space at one point with relation to the car.
- It will be readily seen with reference to the foregoing description and accompanying drawings that I have provided a reliable and efficient car door which is capable of withstanding rough usage and may be readily moved into an out of the way position in such a way that the receiving capacity of the car is in no way lessened.
- 105 It is obvious that when the grain is to be unloaded the lower door section is first moved outwardly from the car to permit the grain to flow therefrom and after this action the upper door is moved out of the way at which time the lower door is swung upwardly and supported after the manner described.
- 110 In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claim.
- 115 What is claimed is:—
- The combination with a car of a grain door comprising separate upper and lower sections, one mounted to swing from a verti-
- 120
- 125
- 130

cal position in the door way to a horizontal position adjacent to the roof and the other mounted to do the same and also move to a position at one side of the door way and three or more parallel transverse rods arranged adjacent to the roof, one adjacent to each side of the door way and the other more remote so that the respective door sections may be swung up between two adjacent rods and cross rods engaging respectively the two parallel rods adjacent the door and one of them and the more remote

parallel rod and being movable longitudinally of said rod to or from a position beneath the respective door section to support the same or permit it to drop.

In testimony whereof I affix my signature in presence of two witnesses.

CARL F. RAKOW.
